DRAFT RIGGING

Harvey J. Lounsbury, Glen Ellyn, Ill., assignor to
 W. H. Miner, Inc., Chicago, Ill., a corporation of
 Delaware

Application December 5, 1932, Serial No. 645,733

6 Claims. (Cl. 213—9)

This invention relates to improvements in draft riggings especially designed for mine cars.

One object of the invention is to provide a combined buffing and draft gear for mine cars, which 5 may be mounted entirely at the end of the car and which is so designed that the capacity in buff is greater than that in draft.

Another object of the invention is to provide 10 a draft rigging for mine cars, which is of simple design, efficient in operation, may be economically manufactured, and easily applied to the car.

A further object of the invention is to provide 15 a draft rigging of the character described in the preceding paragraph, wherein both the buffing and draft forces are transmitted through a coupler member and the resistance to movement of the coupler in buff is greater than the resistance in draft, thereby taking care of the relatively heavier buffing shocks.

20 Still another object of the invention is to provide a coupler for mine cars so arranged that it cooperates with the draft rigging of the car in both buff and draft and mounted in such a manner that it may be readily adjusted to properly 25 register and engage with the coupler of an adjacent car.

Other objects of the invention will more clearly appear from the description and claims herein-after following.

30 In the drawing, forming a part of this specification, Figure 1 is a part top plan view and a part horizontal sectional view of one end of a mine car, illustrating my improvements in connection therewith. Figure 2 is a front end elevational view of the structure illustrated in Figure 1. And Figure 3 is a vertical sectional view, corresponding substantially to the line 3—3 of Figure 2.

In said drawing, 10 designates the vertical end 40 wall of a mine car and 11 the floor of said car. As shown in Figure 2, the middle section of the floor of the car is depressed, the bottom of said depressed portion being formed by a longitudinally extending plate 12 and the side walls being 45 formed by beams 13—13, which are in effect sill members extending lengthwise of the car. The beams 13—13 have top and bottom flanges 14 and 15, the top flange of each beam being fixed to the bottom of the car, and the bottom flange 50 supporting the floor plate 12.

My improved mine car draft rigging comprises broadly a supporting casting A; a movable casing B; a yoke C; a follower plate D; a coupler E; two springs F—F; and two springs G—G.

55 The casting A has a platelike front wall 16,

which extends upwardly beyond the bottom end edge of the wall 10 of the car and is secured to said wall 10 by any suitable means, such as rivets shown in Figures 2 and 3. The casting A is provided with a central pocket 17, which has 5 a vertical rear end wall 18 offset inwardly with respect to the platelike wall 16. The pocket 17 accommodates the yoke C, and the wall 18 forms a rear stop for the yoke. At the forward side, the platelike wall 16 is provided with spaced top 10 and bottom flanges 19 and 20 and vertically extending webs 21—21 connecting the top and bottom flanges. The flanges 19 and 20 and the webs 21—21 define a housing-like structure adapted to accommodate the inner end of the 15 casing B for sliding movement. The flange 20 at the bottom of the casting A is offset below the bottom wall of the pocket 17. The top and bottom flanges 19 and 20 are provided with aligned openings 22—22 adapted to accommodate 20 stop pins 23—23 which cooperate with the casing B to limit outward movement thereof.

The casing B has a vertical front end wall 24, spaced vertical side walls 25—25 extending rearwardly from said wall 24, and horizontally disposed top and bottom walls 26—26. Centrally of the casing B the front wall 24 is provided with an opening 27 which accommodates a portion of the yoke C, as herein-after pointed out. The opening 27 has side walls 28—28 which extend 30 rearwardly from the wall 24 and connect with the top and bottom walls 26—26 of the casing B. The vertical rear edges of the walls 28—28 form front stops for the follower plate D, as herein-after pointed out. At opposite sides of the casing 35 B the top and bottom walls 26—26 are slotted, as indicated at 29—29, to accommodate the stop pins 23—23. As will be evident, the casing B is thus connected to the supporting casting A for limited movement toward and away from the 40 end of the car, the stop pins 23—23 positively limiting outward movement of the casing B, thereby holding this casing stationary during a draft action of the rigging.

The yoke C has horizontally disposed top and 45 bottom arms 30—30 connected by a vertical rear end section 31 and a vertical front end section 32. The section 32 is provided with a journal opening 33 for receiving a connecting member of the coupler E. The yoke C is disposed within 50 the casing B in alignment with the opening 27 of the front wall 24 of said casing. As most clearly shown in Figures 1 and 3, the rear end of the yoke C is slidably guided in the pocket 17 while the front end thereof is guided between 55

the vertical side walls 28-28 of the opening 27 of the casing B.

The follower plate D is of substantially rectangular outline and is disposed within the forward end of the yoke C, as most clearly shown in Figures 1 and 3. The follower plate D is of such a width that the opposite ends project beyond the sides of the yoke C and normally engage the inner end edges of the side walls 28-28 of the opening 27 of the casing B, thereby limiting forward movement of the follower plate D. The follower plate D cooperates with the springs F-F, which are disposed within the yoke and have their rear ends bearing directly on the vertical rear end section 31 of said yoke.

The springs G-G are arranged at opposite sides of the mechanism and are disposed within the casing B, having their forward ends bearing on the inner side of the front wall 24 of said casing and having their rear ends bearing on the vertical wall 16 of the supporting casting A. As shown, the walls 24 and 16 are preferably provided with projecting bosses which engage within the coils of the springs G-G so as to hold the same properly centered.

The coupler E has a pair of forwardly projecting fingerlike members 34 and 35 provided with vertically aligned coupler pin receiving openings 36-36. As most clearly illustrated in Figure 3, the fingers 34 and 35 are horizontally disposed and spaced apart vertically such a distance as to receive the projecting finger 34 of a similar coupler therebetween. A cooperating coupler of this type is illustrated in dotted lines in Figure 3. The fingers 34 and 35 of the coupler E are spaced unequal distances from the top and bottom sides of said coupler, the upper finger 34 being spaced such a distance from the top of the coupler as to accommodate the finger 35 above said finger 34. As will be understood, the coupler shown in dotted lines in Figure 3 is reversed with respect to the coupler E, which is shown in full lines, so that the parts of these two couplers will properly register. The cars when coupled together are connected by a coupler pin 37, which is engaged through the openings 36-36 and 36-36 of the fingers 34 and 35 of the two couplers. In order to provide for adjustment about the longitudinal axis of the coupler so as to bring the same to a position to properly register with the coupler of the adjacent car, the coupler E, as shown in Figure 3, is provided with a rearwardly extending, cylindrical, boltlike connecting portion 38, which is journaled within the opening 33 at the forward end of the yoke C. The inner end of the extension 38 is preferably threaded and receives a nut 39, which serves to anchor the coupler to the yoke C. The main body portion of the coupler E is in the form of a vertically disposed platelike member 40, which is of such a size as to extend beyond the edges of the opening 27 of the front wall of the casing B, as clearly shown in Figures 1 and 3, thereby providing shouldered engagement between the coupler E and the casing B so that the casing will be forced to move rearwardly with the coupler in buff.

In applying my improved draft rigging to the mine car, the supporting casting A is first secured to the end of the car by riveting the same to the vertical wall 10 and securing vertically upstanding flanges 41-41 at opposite sides of said casting to the vertical sections of the beams 13-13. The casing B, with the other parts assembled therewith, is then applied to the sup-

porting casting A and connected thereto by the pins 23-23. Before application of the casing B to the supporting casting A, the yoke C, follower plate D, springs E-E and F-F, and the coupler E are assembled with said casing in the following manner: The yoke is entered through the rear of the casing B with the front end section thereof extending into the opening 27 of the front wall of said casing. The coupler E is then attached to the front end section of the 10 yoke C, and the follower plate D placed within the yoke. Next, the springs F-F are inserted between the follower plate D and the rear end section 18 of the yoke. The springs G-G are placed within the casing B at any time before 15 the application of said casing to the casting A.

In the operation of my improved draft rigging, inward movement of the coupler E in buff causes inward movement of the casing B, thereby compressing the springs G-G against the 20 vertical wall of the supporting casting A. At the same time, the follower plate D is carried inwardly by the casing B, thereby compressing the springs F-F against the vertical rear end section 31 of the yoke C, which at this time is held 25 stationary by engagement with the stop wall 18 of the pocket 17. Inward movement of the casing B will be limited by engagement with the supporting casting A. When the buffing force is reduced, the expansive action of the springs 30 F-F and G-G returns the parts to normal position, outward movement of the casing B being limited by the stop pins 23-23.

When a pulling or draft action is applied to the coupler E, the yoke will be moved outwardly 35 therewith, thereby compressing the springs F-F against the follower plate D, which at this time is held stationary by engagement with the inner ends of the walls 28-28 of the casing B. As will be understood, the casing at this time is held 40 against outward movement by the stop pins 23-23.

I have herein shown and described what I now consider the preferred manner of carrying out my invention, but the same is merely illustrative and I contemplate all changes and modifications that come within the scope of the claims 45 appended hereto.

I claim:

1. In a draft rigging for mine cars, the combination with a supporting member fixed to the end of the car; of a casing slidably carried on said supporting member, said casing having a front wall provided with a central opening; spring means at opposite sides of said opening opposing movement of said casing inwardly toward the end of the car; a coupler, said coupler overlapping the edges of said opening and engaging said front wall of the casing to move the latter inwardly of the end of the car; additional spring means opposing inward movement of the casing; and means connected to the coupler and extending through said opening for transmitting draft forces to said additional spring means. 65

2. In a draft rigging for mine cars, the combination with a supporting member fixed to the end of the car; of a casing slidably carried on said supporting member for movement inwardly toward the end of the car, said casing having a front wall provided with an opening there-through; means for limiting outward movement of said casing; springs within the casing at opposite sides of said opening buttressed against said supporting member and yieldingly opposing 70

inward movement of the casing; a coupler engaging said front wall of the casing at opposite sides of the opening for moving said casing inwardly upon inward movement of the coupler; additional 5 spring means opposing inward movement of the casing; and a yoke movable in the opening of said front wall of the casing, said yoke being connected to the coupler and movable therewith in draft for compressing said additional spring 10 means.

3. In a draft rigging for mine cars, the combination with a supporting member fixed to the end of the car; of a casing slidingly carried on said supporting member for movement inwardly 15 toward the end of the car, said casing having a front wall provided with a central opening; means for limiting outward movement of said casing; springs within the casing at opposite sides of said opening and bearing on said front wall, said 20 springs also bearing on said supporting member and yieldingly opposing inward movement of the casing; a coupler engaging the front wall of said casing adjacent to said opening in the front wall for moving said casing inwardly upon inward 25 movement of the coupler; additional spring means opposing inward movement of the casing; a yoke connected to the coupler, said yoke being in alignment with the opening of the front wall of the casing and abutting said supporting 30 member to prevent movement of the yoke in buff; a front follower within the yoke having shouldered engagement with the casing adjacent to the opening of said front wall to prevent outward movement of the follower in draft and effect inward movement of the follower with the casing in buff; and a spring within the yoke bearing at opposite ends on the front follower and rear end of the yoke.

4. In a draft rigging for mine cars, the combination with a supporting casting fixed to the end of the car; of a follower casing slidingly carried on said casting for movement lengthwise of the car; stop means for limiting outward movement 40 of the casing; springs seated on said casting and yieldingly opposing inward movement of the casing; a coupler, said coupler having shouldered engagement with the casing to transmit buffing forces to the same; a yoke connected to the coupler, said yoke having a transverse rear end section normally bearing on said casting; a front follower plate within the yoke, said follower plate 45 having shouldered engagement with the casing; and being movable inwardly with said casing; and

a spring within the yoke and bearing at opposite ends on said follower plate and the transverse rear end section of the yoke.

5. In a draft rigging for mine cars, the combination with a supporting casting fixed to the end 5 of the car, said casting having a vertically disposed abutment wall and a central pocket having a vertical wall rearwardly offset from said abutment wall; of a yoke extending into said pocket and having its inner end normally bearing on said 10 wall of the pocket; a coupler; a front follower plate within the yoke; a spring within the yoke engaging said front follower plate; a follower casing slidingly carried by said supporting casting, said follower casing having a vertical front 15 wall on which the inner end of the main body portion of the coupler normally bears, said coupler having a rearwardly projecting shank portion connected to the yoke and extending through the opening of the front wall of said casing; and 20 springs at opposite sides of the casing yieldingly opposing movement of the latter, said springs bearing at opposite ends on said abutment wall of the casting and the front wall of the casing, said casing having inwardly projecting flanges 25 bearing on the outer side of said front follower plate.

6. In a draft rigging for mine cars, the combination with a supporting member fixed to the end of the car; of a follower member movable 30 toward and away from the supporting member, said follower member having a central opening therethrough; shock absorbing means at opposite sides of said opening yieldingly opposing movement of said follower member toward the 35 supporting member; means for limiting outward movement of the follower member; a coupler, said coupler being provided with a shank having shouldered engagement with said follower member adjacent to said opening to move the latter 40 inwardly in buff; a stem on the coupler shank extending into said opening; a yoke connected to said stem of the coupler shank, said yoke being normally held against inward movement by engagement with said supporting member; a fol- 45 lower plate within the yoke, said follower plate bearing on the follower member adjacent to said opening and being movable with the follower member in buff; and shock absorbing means with- 50 in the yoke opposing relative movement of said yoke and follower plate.

HARVEY J. LOUNSBURY.
